VIBRATOR CHUTE

Paul Eppenberger, Amriswil, Switzerland, assignor to
Gebrueder Buehler, Uzwil, Switzerland, a Swiss firm

Application July 16, 1957, Serial No. 672,223

Claims priority, application Switzerland July 24, 1956

3 Claims. (Cl. 209—344)

Coupled, counterrunning vibrator chutes such as delivery or conveyer troughs, riddles or vibrating screens are much used, for example in transport means, machines for cleaning or scouring semolina, farina or middlings, grain separators and the like. They are particularly suited for use in the air-compensation in closed boxes.

My present invention discloses an advantageous construction of such shaking or vibrating chutes, in which the conditions of acceleration and deceleration are substantially improved by virtue of the introduction of frictional forces in the suspension gear.

The present invention relates to a conveying or delivery apparatus comprising two coupled reciprocable shaking chutes such as delivery troughs, riddles or the like. Said apparatus, as known per se, comprises a drive shaft journaled on one of said chutes and provided with an eccentric which through a coupling rod is pivotally connected to the other chute. As disclosed by the present invention, said known apparatus is characterized in that one of the two chutes is suspended by hangers, its position of rest being determined by springs engaging said hangers, and the other chute is supported by slide shoes or slippers.

One form of the invention is schematically shown, by way of example and as applied to a machine for cleaning or scouring semolina, farina or middlings. In the drawing, Fig. 1 is a side view of the machine, and Fig. 2 is a front elevation of the machine in a larger scale and in direction of the arrow B in Fig. 1.

From the machine frame 1 a first vibrator chute 2 formed as sieve carrier is suspended by hangers 3. A second vibrator chute 5, formed as delivery trough, is carried through slide shoes 6 on corresponding counterface-brackets 7 secured to frame 1.

As generally known, the products of the grinding operation are poured on the sieves of carrier 2. The material passing through the sieves falls into delivery trough 5. A suction channel 8 draws air through sieve carrier 2 to remove the bran particles.

To sieve carrier 2 are fixed two brackets 10 in which a drive shaft 11 provided with an eccentric 12 is journaled. The latter is pivotally connected to trough 5

2

through a coupling rod 13. To drive shaft 11 is fixed at each end a pulley 14 and 15 respectively, of which pulley 14 is driven through a motor 17. As the traction of belt 16 is generally at right angles to the direction of vibration, the shaking movement is not disturbed. To compensate the unbalance of eccentric 12, counterpoises 19 are fixed to the two pulleys 14 and 15.

The position of rest of sieve carrier 2 is determined by springs 22 which engage the hangers 3. A turnbuckle 23 allows of adjusting the length of the hangers 3. Another turnbuckle 24 allows of adjusting the spring tension. A set screw 25 allows of changing the point of attack of the springs 22 on the hangers 3. By these means it is possible, for example, to vary the inclination of the hangers 3 in the position of rest of carrier 2 and, thereby, to regulate the angle of throw of the sieves of carrier 2. When making the hangers 3 of different lengths sieve carrier 2 may be made sloping, which may be desirable in certain applications.

15 The stroke of sieve carrier 2 and of delivery trough 5 depends on the eccentricity of eccentric 12 with respect to shaft 11 and on the ratio of the masses of sieve carrier 2 and trough 5. A variable weight 27 allows of changing said ratio. In lieu of weight 27, variable weights may be attached to sieve carrier 2.

20 Chute 5 is provided with an inclined bottom 28. When the inclination is in the other direction, the direction of delivery or feed is changed. Such inclined bottoms are known per se and may be made of one slope throughout or of subdivided slope or foldable or reversible.

25 What I claim as new and desire to secure by Letters Patent, is:

1. In a conveyer, in combination: a pair of reciprocable vibrator chutes, a drive shaft connected with one of said chutes, an eccentric on said shaft, a coupling rod having one end pivotally connected to the other of said chutes and another end operatively connected with said eccentric, a plurality of hangers for suspending one of said chutes, spring means connected with said hangers for determining the position of rest of said last mentioned chute, and slide shoes for carrying the other of said chutes.

2. The structure as set forth in claim 1, further comprising variable weight means connected with one of said chutes for changing the ratio of masses of said chutes.

3. The structure as set forth in claim 1, further comprising at least one counterpoise attached to said shaft for compensating the unbalance of said eccentric.
